DESIGN FOR A DECK OF PLAYING CARDS

Edward A. Klumpp and Nathan S. Harris, Chicago, Ill., assignors to Arreco Playing Card Company, Chicago, Ill., a corporation of Illinois

Application February 19, 1942, Serial No. 105,890

Term of patent 3½ years

To all whom it may concern:

Be it known that we, Edward A. Klumpp and Nathan S. Harris, citizens of the United States, residing at Chicago, in the county of Cook and State of Illinois, have invented a new, original, and ornamental Design for a Deck of Playing Cards, of which the following is a specification, reference being had to the accompanying drawing, forming part thereof.

The drawing shows the face cards and joker of the deck of cards embodying our new design. The other cards and the backs of the playing cards are conventional.

We claim:

The ornamental design for a deck of playing cards, as shown and described.

EDWARD A. KLUMPP.
NATHAN S. HARRIS.
